UNITED STATES PATENT OFFICE.

GEORGE GODDU, OF WINCHESTER, AND FRED L. MACKENZIE, OF BEVERLY, MASSACHUSETTS, ASSIGNORS TO UNITED SHOE MACHINERY CORPORATION, OF PATERSON, NEW JERSEY, A CORPORATION OF NEW JERSEY.

FASTENING-INSERTING MACHINE.

Application filed August 29, 1921. Serial No. 496,200.

To all whom it may concern:

Be it known that we, GEORGE GODDU and FRED L. MACKENZIE, citizens of the United States, residing at Winchester, in the county 5 of Middlesex, and Beverly, in the county of Essex, respectively, and State of Massachusetts, have invented certain Improvements in Fastening-Inserting Machines, of which the following description, in connection with the accompanying drawings, 10 is a specification, like reference characters on the drawings indicating like parts in the several figures.

This invention relates to shoe machinery, 15 for example to such machines as are used for inserting fastenings, and has for its object to provide improved mechanism for varying the operation of such machines on the work, as may frequently be rendered 20 necessary or desirable by dissimilarity in character of the separate pieces of work operated upon or of different parts of the same piece of work.

The invention will be hereinafter described, by way of example, as applied to a machine for inserting loose nails of the type disclosed in United States Letters Patent to Fred L. Mackenzie No. 1,262,820, granted April 16, 1918. In order to adapt 25 machines of that type for operation on pieces of shoe stock of different thicknesses or on stock which varies in thickness at the points where different nails are inserted, the raceways of such machines are formed 30 with a plurality of slots adapted to contain nails of different lengths, and means are provided for causing nails of relatively 35 great length to be supplied to the fastening inserting mechanism for insertion into 40 relatively thick stock and for causing nails of less length to be supplied to the fastening inserting mechanism when relatively thin stock is being operated upon. The conditions which require change in the length 45 of the nails being inserted also frequently make necessary a change in the position 50 of the gage by which the work is guided in the operation of such machines. For example, when nailing around the edge of 55 the sole of a shoe, the thickness of the stock through which the nails are driven is frequently greater at the forepart than in the shank by reason, for instance, of the inter-

position of a half sole or "tap" between the outsole and insole at the forepart. Consequently, it is advisable to insert a longer nail in the forepart than in the shank. The edge of the outsole also frequently projects farther beyond the edge of the insole at the forepart than in the shank, for which reason 55 the edge gage should preferably be moved away from the plane of operation of the fastening inserting mechanism upon the initiation of the insertion of long nails to cause the row of nails to be spaced farther from 60 the edge of the shoe at the forepart than in the shank.

It is, accordingly, an object of the invention to provide improved means for varying the performance of an operation in the manufacture of shoes in accordance with, or under the control of, variation in the shoe part or parts upon which the operation is performed. Thus an embodiment of the invention, for example in a fastening 75 inserting machine, may comprise means for controlling the relative position of the gage and the fastening inserting instrumentalities of the machine arranged to vary the spacing of the row of fastenings from the 80 edge of the work in accordance with a physical characteristic of the work. The illustrated machine is provided with a double raceway which is shifted simultaneously 85 with the gage by mechanism controlled by the thickness of the work to cause the row of nails to be spaced at a variable distance from the edge of the work, both the length of the nails and the distance of the row of 90 nails from the edge of the work being thus controlled by the thickness of the sole of the shoes operated on by the machine.

Since the illustrated machine is particularly designed for use in "all-round" nailing in the manufacture of nailed shoes, it is 95 so arranged that the shorter nails which are inserted in the shank portion of the shoe are located nearer the edge than the longer nails which are inserted in the thicker forepart of the shoe and which it is desirable to have 100 spaced further from the edge to permit the use of a so-called "extension sole".

This application is a continuation in part of an application having Serial No. 270,502, filed January 10, 1919 by George Goddu and 105 Fred L. Mackenzie upon which United

States Letters Patent No. 1,399,765, were granted Dec. 13, 1921.

Although the invention will hereinafter be described as embodied in a machine for inserting loose nails, it is recognized that the use of the invention is not restricted thereto but that the invention in some of its aspects may have other applications including incorporation in machines of other types than fastening inserting machines. Moreover, the illustrated mechanism may be materially modified without departing from the scope of the invention as defined in the claims.

Other objects and features of the invention will appear as the description proceeds and will be pointed out in the appended claims. In the drawings,

Fig. 1 represents a fastening inserting machine of the type disclosed in said patent to Mackenzie No. 1,262,820, with the present invention embodied therein;

Fig. 2 is a side elevation with the raceways in section of the raceway shifting and part of the gage controlling mechanism of the machine of Fig. 1;

Fig. 3 is a perspective view with parts broken away of certain pawl tipping mechanism of Fig. 2;

Fig. 4 is a perspective view of portions of the raceway shifting and gage shifting mechanism; and

Fig. 5 is a perspective view of the gage and some of its associated parts.

The machine in which the invention is herein illustrated as embodied comprises a column 2 which supports a head 4 upon the front end of which are mounted fastening inserting instrumentalities including an awl 6 operative to penetrate and feed the work. A gage 8 is carried on the under side of the head adjacent to the point of insertion of the fastenings and acts to determine the spacing of the fastenings from the edge of the work.

Means are provided for controlling the inserting mechanism so as to cause it to insert selectively nails of different lengths. In the illustrated construction, such means is generally of the type disclosed in said patent to Mackenzie No. 1,262,820, and for convenience in comparing the machine herein disclosed with that of said patent, similar reference numerals will be used to designate similar parts. Slide 280, upon which is mounted an actuator in the form of a double pawl 502 for shifting the raceway, is reciprocated by connections with a lever 182 to bring said pawl into and out of engagement with one or the other of two shoulders 302 and 306 upon a horizontal slide 304. To prevent breakage in case of excessive strain, as might occur if the raceway should become jammed, lever 182 is provided with two arms 183 and 185, connected by a spring 187 sufficiently stiff to cause the lever to function

under normal conditions as a rigid member, but arranged to yield if any of the parts operated thereby should become jammed. Arm 185 of lever 182 is provided with a segment 296 meshing with a rack 294 mounted upon slide 280 so that oscillation of lever 182 causes reciprocation of the double pawl 502. Lever 182 also carries a cam roll which enters a cam groove in cam 48 upon the shaft 20 of the machine. The connections between the slide 304 and the double raceway 264, which has two slots designed to receive relatively long and short nails respectively, comprise, as shown in the patent to Mackenzie above mentioned, oppositely threaded rods 308 and 310 connected by an adjusting nut 312, the rod 308 being pivotally connected to the lug 314 upon the side of the double raceway. The rod 310 receives in an opening at one end an eccentric carried on the lower end of a rock shaft 318 mounted in a bearing in the bracket 272, said rock shaft having formed upon its upper end a pinion 320 with which meshes a segment rack 322 formed on the end of the rock arm 324 which is clamped upon the upper end of the rock shaft 326 also mounted in a bearing in the bracket 272 and carrying at its lower end a gear segment 328 which meshes with rack teeth 230 on the slide 304. The shifting movement of the slide 304 is sufficient to turn the eccentric upon shaft 318 around from one dead center to the other with respect to the rod 310 so that the raceway is positively shifted and positively held in either of its positions.

Pawl tipper 606, arranged to operate double pawl 502, comprises two arms 608, 610 which carry respectively the dogs 536, 538, and a circular body portion provided with a hub mounted to turn freely upon a shaft 614. The body portion of the tipper 606 is cut away below its hub to form a segmental opening 616 through which projects a stop 618 carried by an arm 620 provided with a hub sleeved upon the hub of the pawl tipper, said arm being given a tendency to turn in a counter clockwise direction (Fig. 2) by a spring 622 coiled about the hub and bearing at one end against a pin 624 upon said arm 620, and at its other end being attached to a clamp collar 626 clamped upon the hub of the pawl tipper. The movement of the arm 620 relative to the pawl tipper 606 is limited in the direction in which the spring tends to turn said arm by a stop 628 (Figs. 2 and 3) adjustable about the periphery of the circular body portion of the tipper.

The pawl tipper is so arranged that it is normally in short nail position, being yieldingly maintained in this position by a spring 636 which is connected at one end to a screw or stud 638 upon bracket 272 by which the raceway shifting mechanism is

carried, and having its other end bent down so that it enters a socket 640 in the outer face of a bell crank lever 642 fulcrumed upon a stud 644 and having at its forward 5 end a short rack 646 which engages teeth 648 in the periphery of the circular body portion of the pawl tipper 606. Between the stud 644 and the pawl tipper 606 the arm of bell crank 642 is provided with an 10 opening which receives a stud 650 serving as a stop for the vertical movement of said arm, the opening being larger in diameter than the stud 650 whereby movement of the arm sufficient to rock or permit the rocking 15 of the pawl tipper between its two pawl tipping positions can take place.

The pawl tipper may be moved into its long nail position either by manual means or automatically in accordance with the demands of the work. The means for effecting the movement of the pawl tipper automatically in accordance with changes in the thickness of the work are operated through connections with the horn 22 or other work 20 support, said connections comprising a two-part lever 464, 468 (Fig. 1) adapted to be put into operative position by a treadle operated cam 476, as more fully described in United States Letters Patent to George 25 Goddu No. 1,011,941, granted December 19, 1911, a toggle 168, 170 normally maintained in straightened position whereby the pressure of a spring 164 is transmitted to the horn 22 to clamp the work against the work 30 abutment 266, and a rod 160 connected at its lower end to pawl carrying slide 162 and at its upper end to one end of a lever 652 (Fig. 4) fulcrumed upon a short shaft 654 in the machine frame, said lever having 35 an arm 656 provided at its end with a rack segment 658 (see Fig. 3). The rack segment 658 meshes with the small rack segment or part of a pinion 660 forming part of multiplying connections carried upon a 40 shaft 662 journaled in the machine frame, the other part of said connections comprising a rack segment 664 formed upon an arc of a circle of a larger radius than the radius of curvature of the rack or pinion 660. The 45 rack 664 meshes with a pinion 666 carried upon the inner end of the rock shaft 614 whereby said shaft is turned as the thickness of the work gaged between the horn 22 and the work abutment 266 varies. 50 Formed integral with the shaft 614 is an enlarged portion 668 carrying a tooth or stop 670 adapted to engage the stop 618 upon the arm 620. Thus horn 22 is operated to measure the work, the measurement being transmitted to rod 160 and lever 652 and being utilized to control the position of tipper 606 and hence to control the fastening inserting and, as hereinafter explained, the position of gage 8.

65 It will be noted that the connections from

the horn 22 to the pawl tipper operating means are of a nature such that the pawl tipper operating means does not partake of the movement of the horn to permit the work to be fed but is moved only upon 70 change in the thickness of the work engaged by the horn.

As already indicated, the connection between the pawl tipper or actuator controlling means and the horn is normally broken 75 between the stop 670 on the shaft 614 and the stop 618 upon the arm 620. The broken connection between the pawl tipper and the horn permits the pawl tipper to be normally maintained in fixed position by the spring 80 636 regardless of changes in the thickness of the work being operated upon so long as the work does not exceed a predetermined thickness. As illustrated, the spring 636 tends to maintain the pawl tipper in its 85 short nail position. When the work increases in thickness, the rock shaft 614 is turned through the connections with the horn hereinabove described in the direction to move the stop 670 (Fig. 3) into engagement with the stop 618 and thus make connection between the pawl tipper and the horn. The stop 618 is free to move away from the stop 628 upon the circular body portion of the pawl tipper 606 but the hub 90 of the arm 620, which carries the stop 618, is connected to the hub of the pawl tipper 606 by the spring 622 which is put under increased tension as the stop 670 tends to move the stop 618 away from the stop 628. 95 The pawl tipper 606 is thus caused to follow the movement of the stop 618 until it comes into its long nail position, or until its movement is limited by the engagement of one side of the opening in the arm 642 with the 100 stud 650. If the increase in thickness of the stock is greater than that required to effect this movement of the pawl tipper, the arm 620 will move out of engagement with the stop 628, the increased tension of the 105 spring tending to hold the pawl tipper steady in its long nail position.

If it is desired to shift the raceway manually, this may be done by depressing treadle 706, which operates through connections 692, 682, 680 (Figs. 1 and 2) to rock lever 642 and thus to shift the pawl tipper, as more fully explained in the Mackenzie Patent No. 1,262,820.

The illustrated machine is provided with 120 an edge gage automatically shiftable in accordance with the shifting of the raceway, so as to cause the insertion of short nails comparatively near the edge of the work, as in the shank of a shoe, and long nails 125 further from the edge of the work, as in the forepart of a shoe provided with a half sole or "tap" in addition to its outsole, as will now be more fully described.

Slidably mounted for rectilinear move- 130

ment on a bracket 800 carried by the machine frame is a gage member or slide 802 having a spring 804 connected thereto and tending to move the gage rearwardly. A set screw 806 disposed to engage a pin 808 depending from the slide adjustably limits the movement of the gage in such direction. To the end that the gage may be automatically moved from one gaging position to another, the slide bar 304 is extended beyond the rack 330 as indicated at 809 and has secured in its end a stud 810 grooved to receive the hooked end of a link 812 joined to the upper end of a lever 814 fulcrumed at 816 to an upwardly extending portion 818 of the bracket 800. The lever 814 is provided at its lower end with teeth meshing with a pinion 820 on a shaft 822 journaled in the bracket 800 and formed with an eccentric portion 824 engaging a lug 826 on the gage slide and operable upon angular movement of the shaft 822 to move the gage forwardly in opposition to the spring 804. A spring 828 connected at one end to a pin 830 on the link 812 and at its other end to the pin 832 retains the link 812 in engagement with the stud 810 but permits it to be readily detached from the stud when desired. The arrangement of the above described parts is such that when the bar 304 is moved in a direction to shift the raceway to short nail position, the extension 809 of the bar, through its connections with the gage, moves it forwardly against the resistance of the spring 804. When, on the other hand, the bar 304 is moved in the opposite direction so as to effect movement of the raceway to a position to deliver long nails, the shaft 822 is rotated to withdraw its eccentric portion whereupon the gage is moved back by the spring.

Having thus described our invention, what we claim as new and desire to secure by Letters Patent of the United States is:

- 45 1. A shoe machine having means for operating about the periphery of a sole, and mechanism for relatively moving the operating means and the work to vary the position upon the sole at which the operation is performed, said means being controlled by a variation in a characteristic of the peripheral portion of the sole operated upon.
- 50 2. A shoe machine having means for operating about the periphery of a sole and means controlled by a variation in a dimension of the sole for varying the position laterally of the sole at which the operation is performed.
- 55 3. A shoe machine having means for operating upon a sole, means for measuring the thickness of the sole and mechanism controlled by the measuring means for varying the position laterally of the sole at which the operation is performed.
- 60 4. A shoe machine having means for op-

erating upon soles, and means for varying the position laterally of the soles at which the operation is performed controlled by the thickness of the soles.

5. A shoe machine having, in combination, a pair of members between which soles may be gripped and fed, means for operating on the soles, means for feeding the soles between said members to the operating means, and means controlled by the extent of relative displacement of said members effected by variation in the thickness of the soles to vary the position at which the operation is performed upon the soles.

6. A shoe machine having an edge gage, and means for shifting the gage toward or from the edge of the work controlled by the thickness of the work.

7. A shoe machine having an edge gage, means for measuring the thickness of the sole of a shoe, and means for shifting the gage toward or from the edge of the sole controlled by the thickness of the sole.

8. A shoe machine having a gage, means for measuring the work, and means for shifting the gage controlled by said measuring means, and operating to shift the gage from one position to another according as the thickness of the work is greater or less than a predetermined critical thickness.

9. A shoe machine having means for operating upon shoe parts, a gage arranged to position the shoe parts with respect to the operating means, and mechanism controlled by a characteristic of the shoe part operated upon for varying the relative position of the gage and the operating means in accordance with variations of said characteristic in an individual piece of work, thereby varying the location at which the operation is performed on different parts of said piece of work.

10. A shoe machine having, in combination, means for operating upon a piece of work, a gage, and means controlled by a variation in a characteristic of the piece of work for causing relative movement of the operating means and the gage arranged automatically to vary the distance from the edge of the piece of work at which the operation is performed on different parts of the same piece of work in accordance with a variation in said characteristic.

11. A shoe machine having, in combination, means for operating upon work, a gage arranged for engagement with the work operated upon, and means controlled by the thickness of the work for causing relative movement of the operating means and the gage automatically to vary the distance from the edge of the work at which the operation is performed.

12. A machine for performing an operation adjacent to the periphery of a piece of work having, in combination, an edge gage,

and means controlled by the thickness of the work for controlling the position of the edge gage transversely of the work.

13. A machine for performing an operation adjacent to the periphery of a piece of work having, in combination, an edge gage, means for measuring the work, and means controlled by the measuring means for shifting the edge gage transversely of the work.

14. A machine for operating upon shoe parts having, in combination, means for feeding the work to the operating means, an edge gage, and means controlled by a characteristic of the shoe part operated upon for controlling the relative position of the edge gage and the feeding means transversely of the work.

15. A machine for operating upon shoe parts having, in combination, means for performing an operation progressively about the peripheries of shoe parts, means for feeding the shoe parts to the operating means, a gage, means for measuring the shoe parts, and means controlled by the measuring means for changing the relative position of the gage and the operating means.

16. A machine for operating upon shoe parts having, in combination, means for feeding the work to the operating means, an edge gage, a pair of relatively movable members between which the work is fed, and means for shifting the edge gage controlled by the relative position of said members.

17. A shoe machine having, in combination, a gage formed to present a bearing surface for engagement with the edge of the work to determine the position at which an operation is performed upon the work, a member shiftable from one position to another under the control of the work according as the thickness of the work is greater or less than a predetermined critical thickness, and means operated by said member to move the gage from one gaging position to another according as the thickness of the work is greater or less than said critical thickness.

18. A shoe machine having, in combination, a gage formed to present a bearing surface for engagement with the edge of the work to determine the position at which an operation is performed upon the work, a slide shiftable from one position to another according as the thickness of the work is greater or less than a certain critical thickness, and connections from the slide to the gage operative to shift the gage from one gaging position to another according as the thickness of the work is greater or less than said critical thickness.

19. A fastening inserting machine hav-

ing, in combination, a gage formed to present a bearing surface for engagement with the edge of the work to determine the spacing of a row of fastenings from the edge of the work, means for measuring the work, a slide shiftable from one position to another according as the thickness of the work is greater or less than a certain critical thickness, and connections from the slide to the gage operative to shift the gage from one gaging position to another according as the thickness of the work is greater or less than said critical thickness.

20. A machine for use in manufacturing shoes comprising, in combination, work-feeding means, means co-operating therewith to measure variation in a characteristic of work fed thereby, an instrumentality to operate on the work, said instrumentality and the work being relatively movable laterally in a rectilinear path, and a connection responsive to the measurement so made to control the relative lateral movements of the work and said instrumentality.

21. A machine for use in the manufacture of shoes comprising, in combination, means to operate on a piece of stock, and means responsive to variation in a characteristic of the stock to control the location of the region operated upon, said controlling means being adjustable to change the amount of variation in the location of said region caused by a given variation in the stock.

22. A machine of the class described having, in combination, fastening inserting means, and means for varying relatively to a characteristic feature of the work the position at which fastenings are inserted in the work controlled by the thickness of the work.

23. A machine of the class described having, in combination, fastening inserting means, and means for varying the distance from the edge of the work at which fastenings are inserted controlled by a dimension of the work.

24. In a fastening inserting machine arranged to insert fastenings of varying character and having means for changing the character of fastenings inserted, a gage operable to position the work relatively to the fastening inserting mechanism by engagement with the edge of the work, and means controlled by a characteristic of the work for moving the gage to different operative positions.

25. In a fastening inserting machine arranged to insert fastenings of varying character and having means for changing the character of fastenings inserted, a gage operable to position the work relatively to the fastening inserting mechanism by engagement with the edge of the work, means

to measure the work, and means controlled by the measuring means for moving the gage to different operative positions.

26. A fastening inserting machine having, in combination, means for inserting fastenings of any one of a plurality of different kinds, mechanism controlled by a characteristic of the work for determining which kind of fastening shall be inserted, 10 a gage for positioning the work with respect to the fastening inserting means, and gage controlling means, controlled by said mechanism, for varying the position of the work and hence of the fastenings inserted 15 in accordance with the kind of fastenings inserted.

27. A fastening inserting machine having, in combination, fastening inserting mechanism, a plurality of sources of fastening supply, means for inserting fastenings from one or another of said sources of supply controlled by a characteristic of the work, a gage, and means controlled by a characteristic of the work for shifting the gage according as the fastenings are inserted from one or another of said sources of supply.

28. A fastening inserting machine having, in combination, fastening inserting mechanism, a plurality of sources of fastening supply arranged to supply fastenings of different characteristics, means for inserting fastenings from one or another of said sources of supply controlled by a dimension of the work, a gage, and means controlled by said dimension of the work for shifting the gage so as to vary the position of the fastenings according as they are taken from one or another of said 40 sources of supply.

29. In a machine of the class described, fastening inserting mechanism constructed and arranged to insert fastenings of varying character, a gage for positioning the work relatively to the fastening inserting mechanism by engagement with the edge of the work, and means controlled by a characteristic of the work for moving the gage from one gaging position to another 50 and for changing the character of fastenings inserted by said mechanism.

30. In a machine of the class described, fastening inserting mechanism constructed and arranged to insert fastenings of varying character, controlling means for the fastening inserting mechanism operable to cause a change in the character of the fastenings inserted by said mechanism, a gage for positioning the work relatively to the fastening inserting mechanism by engagement with the edge of the work, and means controlled by a characteristic of the work for effecting movement of the gage 60 from one gaging position to another.

31. In a machine of the class described, 65 fastening inserting mechanism constructed and arranged to insert fastenings of varying character, controlling means for the fastening inserting mechanism operable to cause a change in the character of the fastenings inserted by said mechanism under the control of a dimension of the work, a gage for positioning the work relatively to the fastening inserting mechanism by engagement with the edge of the work, 70 and means controlled by a dimension of the work for effecting movement of the gage from one gaging position to another. 75

32. In a machine of the class described, 80 fastening inserting mechanism constructed and arranged to insert fastenings of varying character, means for feeding the work relatively to the fastening inserting mechanism to cause the insertion of a row of fastenings in the work, means controlled by a characteristic of the work for changing the character of fastenings inserted by the fastening inserting mechanism, a gage arranged for engagement with the edge of the work to determine the spacing of the fastenings from the edge of the work, and means operated by the fastening changing means for shifting the gage so as to change the spacing of the row of fastenings from 85 the edge of the work. 90

33. A fastening inserting machine having, in combination, nail inserting mechanism, means for supplying thereto alternatively nails of different lengths, means controlled by the thickness of the work for controlling the nail supplying means to cause the presentation in fastening inserting position of nails of a length appropriate to the work, a gage, and means controlled by the thickness of the work to vary the position at which the nails are inserted in accordance with the thickness of the work. 105

34. A fastening inserting machine having, in combination, means for inserting long or short nails, means controlled by the thickness of the work for insuring the insertion of short nails in such portions of the work as are of less than a certain critical thickness and the insertion of long nails 110 in such parts of the work as are of greater than that critical thickness, an edge gage, and means controlled by the thickness of the work for shifting the gage to cause the insertion of short nails at one distance 115 from the edge of the work and the insertion of the long nails at a different distance from the edge of the work. 120

35. A fastening inserting machine having, in combination, two raceways constructed respectively to deliver nails having different characteristics, means for bringing the appropriate raceway into nail delivering position controlled by a characteristic of the 125

work, a gage, and means controlled by a characteristic of the work for shifting the gage according as one or the other of said raceways is brought into nail delivering position.

36. A fastening inserting machine having, in combination, a gage formed to present a bearing surface for engagement with the edge of the work to determine the spacing of a row of fastenings from the edge of the work, a member shiftable from one position to another under the control of the work according as the thickness of the work

is greater or less than a predetermined critical thickness, and means operated by said member to move the gage from one gaging position to another according as the thickness of work is greater or less than said critical thickness, constructed and arranged to hold the gage in whichever gaging position it may occupy.

In testimony whereof we have signed our names to this specification.

GEORGE GODDU.
FRED L. MACKENZIE.
